(57) **CLAIM**

The ornamental design for a grip joint for a video camera, as shown and described.

DESCRIPTION

FIG. 1 is a front, bottom, right perspective view of a grip joint for a video camera showing our new design;

FIG. 2 is a bottom, left perspective view thereof;

FIG. 3 is a front elevational view thereof;

FIG. 4 is a top plan view thereof; and,

FIG. 5 is a bottom plan view thereof.

The broken lines illustrating portions of the grip joint for the video camera form no part of the claimed design. Specifically, the evenly spaced broken lines are for the purpose of depicting portions of the article or environmental structure and forms no part of the claimed design. The dash dot dash broken lines are for the purpose of depicting boundaries of the claimed design and forms no part of the claimed design.
